Patented Sept. 23, 1924.

1,509,362

UNITED STATES PATENT OFFICE.

JOHN MARSHALL, OF SWARTHMORE, PENNSYLVANIA, ASSIGNOR TO E. I. DU PONT DE NEMOURS & COMPANY, OF WILMINGTON, DELAWARE, A CORPORATION OF DELAWARE.

HIGH EXPLOSIVE.

No Drawing.

Application filed April 25, 1922. Serial No. 556,420.

To all whom it may concern:

Be it known that I, JOHN MARSHALL, a citizen of the United States, and a resident of Swarthmore, in the county of Delaware and State of Pennsylvania, have invented 5 certain new and useful High Explosives, of which the following is a specification.

My invention relates to blasting explosives containing finely comminuted propellant powders.

By "propellant powder" I mean to include the several varieties of pyro powders and cordites on hand in this country as excess stores following the war. The propellant powders may be comminuted by any 15 desirable type of grinding or disintegrating process.

Previous to my invention, ground propellant powders have been used in conjunction 20 with sodium nitrate or other mineral nitrates to form blasting explosives. However, such explosives have been very dusty to manufacture, and hence dangerous to make, and have been extremely bulky and 25 free-running.

In co-pending application Serial No. 527,488, there has been described a method of overcoming these difficulties by the addition during mixing of a relatively small percentage 30 of liquid explosive, such as nitro-glycerine.

I have now discovered that satisfactory results are also obtained by the addition to the explosive during mixing of a similar 35 amount of aromatic nitro-compound liquid at the temperature of mixing, or at least capable of becoming gelatinized with the powder at this temperature. For this purpose I may preferably use such nitro-benzenoid materials as nitrobenzene, liquid dinitrotoluene, liquid trinitrotoluene, or nitrated solvent naphtha or mixtures of such 40 materials.

The percentage of aromatic nitro-compound used may vary as a rule from about 45 1 to 10% based on the weight of the finished explosive. A typical example of the composition of my explosive is:

	Per cent.
Aromatic nitro-compounds	5
Nitrocellulose (ground smokeless powder)	57
Sodium nitrate	37
Chalk	1

These proportions might be varied so as to contain 1 to 10% aromatic nitro-compounds, 30 to 90% ground smokeless powder, and from 0.0 to 60% sodium nitrate.

The composition may also be changed in 60 that ground cordite may be used in place of the ground smokeless powder, or in place of a portion of it.

In addition, other materials might be used, such as wood pulp, corn meal, flour, 65 etc., or other materials ordinarily used in the manufacture of dynamite. In place of sodium nitrate I may use other alkali-forming-metal nitrates, as, for example, potassium nitrate or barium nitrate. I may also 70 vary the fineness of my ingredients over a wide range. I have found however, that the most satisfactory results are given when the propellant is ground so that at least 100% passes a 20 mesh screen and at least 75 20% passes a 100 mesh screen.

In the manufacture of this explosive I have found that it is essential to mix the materials thoroughly and for a sufficient 80 length of time to insure that the gelatinization of the ground propellant with the aromatic nitro-compound is complete. The length of time which this gelatinization takes will depend upon the method of mixing and other factors, such as temperature, 85 moisture content of ingredients and size of charge. For example, when working at a temperature of from about 65 to 120° F. with a mixing charge of from 600 to 1100 lbs. having a moisture content of from 0 to 90 2%, the aromatic nitro-compound being dinitrotoluene melting at 35° C., and using a mixer of the type ordinarily used in this country for the manufacture of dynamite, the mixing period should be not less than 15 95 minutes. I have found that if the materials are mixed for too short a time, for example 2 to 3 minutes, the cartridges become hard and insensitive on storage.

I have also found that when using more 100 than 10% nitro-aromatic compounds, it is impossible to prevent hardening of the explosive even by prolonging the time of mixing. The satisfactory results obtained with this new explosive are believed to be due to 105 the fact that by using a relatively low percentage of aromatic nitro-compound, and mixing at the proper temperature and for the proper time, I obtain complete gelatinization of the aromatic nitro-compound 1

with the nitrocellulose, with no subsequent gelatinization after mixing.

To increase the sensitiveness of my new explosive compositions I may incorporate 5 a small percentage of powdered aluminum, for example from about 0.3 to 5%.

I claim:

1. A blasting explosive composition comprising more than 25% of a finely com- 10 minuted propellant powder, and from about 1 to 10% of an aromatic nitro-compound completely gelatinized with said powder.

2. A blasting explosive composition comprising more than 25% ground smokeless 15 powder and from about 1 to 10% of dinitrotoluene.

3. A blasting explosive composition comprising from about 30 to 90% of a finely 20 comminuted propellant powder, and an aromatic nitro-compound capable of becoming gelatinized with said powder at a temperature below 120° F., the amount of said 25 aromatic nitro-compound being less than 10% but sufficient to substantially prevent the formation of dust during normal handling of said explosive composition.

4. A blasting explosive composition comprising from about 30 to 90% of a finely 25 comminuted propellant powder, and an aro-

matic nitro-compound which is liquid at a 30 temperature below 120° F., the amount of said aromatic nitro-compound being less than 10% but sufficient to substantially prevent the formation of dust during normal handling of said explosive compositions. 35

5. A blasting explosive composition comprising more than 25% of a finely com- 40 minuted propellant powder, and from 1 to 10% of a nitrobenzenoid compound capable of becoming gelatinized with said powder at a temperature below 120° F.

6. An explosive composition comprising more than 25% of a finely comminuted 45 propellant powder, from about 1 to 10% of an aromatic nitro-compound completely gelatinized with said powder, and sodium nitrate.

7. An explosive composition comprising more than 25% of a finely com- 50 minuted propellant powder, from about 1 to 10% of an aromatic nitro-compound completely gelatinized with said powder, from about 0.3 to 5% of powdered aluminum, and sodium nitrate.

In testimony whereof I affix my signature.

JOHN MARSHALL
